UNITED STATES PATENT OFFICE.

TALY C. THARALSON, OF JAMESTOWN, NORTH DAKOTA.

TRACE-CARRIER.

1,375,068.

Specification of Letters Patent. Patented Apr. 19, 1921.

Application filed July 20, 1918. Serial No. 245,894.

To all whom it may concern:

Be it known that I, TALY C. THARALSON, a citizen of the United States, residing at Jamestown, in the county of Stutsman and State of North Dakota, have invented certain new and useful Improvements in Trace-Carriers, of which the following is a specification, reference being had to the accompanying drawings.

10 This invention relates to harness, and particularly to the trace carriers thereof, such as are used on work harness, and particularly to trace carriers which are used on "three-ring" and "five-ring" harness.

15 The general object of this invention is to provide a trace carrier of this description which is so constructed that it may be readily replaced on the harness by a new trace carrier in case the old trace carrier

20 breaks.

A further object is to provide a trace carrier having a hook so constructed that it will permit the engagement therewith of two chain links or two cockeyes, and further to 25 so form the hook that there will be no danger of the lines becoming caught under the hook.

Other objects will appear in the course of the following description.

30 My invention is illustrated in the accompanying drawings, wherein:—

Figure 1 is a fragmentary plan view of a portion of a "five-ring" breeching showing my trace carrier applied thereto;

35 Fig. 2 is a plan view of the trace carrier partly in section;

Fig. 3 is a side elevation of the trace carrier; and

Fig. 4 is a plan view showing my trace 40 carrier applied to a "three-ring" breeching.

Referring to the drawings, it will be seen that my improved trace carrier comprises a body 10 of metal stock, circular in cross section, which body has the form of an annulus, the opening in the annulus being defined by outwardly bent portions 11 disposed in parallel relation to each other and perforated to provide eyes. Formed integral with the body 10 is the upwardly extending hook 12 disposed diametrically opposite the opening in the body and which extends toward the opening of the carrier and then extends downward and toward the base of the hook, the bill 13 of this hook 55 being disposed in the same plane as the body 10. The eyes 11 are connected by means of

a screw or like member 14, which has a head at one end engaging in a countersunk recess on one of the eyes and which has a substantially uniform diameter, and is 60 screw-threaded for engagement with the other eye. Surrounding this screw 14 is a freely rotatable sleeve or bushing 15.

In Fig. 1, I illustrate the trace carrier as applied to what is known as a "five-ring" 65 breeching, which includes the ring 16, the back straps 17, the straps 18, to which the trace carriers are applied in the manner heretofore stated, and the hip straps 19, there being two hip straps for each 70 trace carrier. The cockeye 20 of the trace 75 carrier is shown as engaged with the hook. The usual chafe strap or pad 22 is attached to the strap 18 and extends beneath the carrier.

In Fig. 4, I show my invention as applied to a "three-ring" breeching wherein 17 designates the back straps and 19 the four hip straps, there being in this case four hip straps instead of but two hip straps illustrated in Fig. 1. This view also shows how the two trace chains 21^a may be engaged with the hook 12. It will be seen that in both Figs. 1 and 4, the hook 12 is of sufficient size as to provide for two chain links 80 or two cockeyes where at present either two hooks must be provided upon the trace carrier or else the one hook is only large enough to permit of the engagement of only one cockeye or trace link therewith. 90

The particular advantage of this invention resides in the ease with which, in case of breakage of the trace carrier, the same may be replaced. The hook on a trace carrier is the part most liable to become broken 95 and when a hook is broken on the trace carriers at present in use, it is necessary to rip three or more laps of the harness in order to replace the broken carrier with a new one. This requires considerable labor and expense. Where my trace carrier is used, however, then in the event that it becomes broken, all that it is necessary to do, in order to replace the broken carrier with a new one, is to remove 100 the screw 14, slip off the hip straps and then apply the new trace carrier, and reengage the screw 14 and the sleeve 15 with the strap 18 in Fig. 1, or with the back straps 17 of the harness arrangement shown in Fig. 4. 110 This ability to readily detach the carrier from the harness and replace with a new

carrier results in a great saving of labor and very greatly reduces the expense of replacement, as compared with the expense and labor incident to replacing trace carriers as at present constructed. It will be noted that the bill 13 of the hook, being disposed in the plane of the body portion 10 of the carrier, there is no danger of the lines getting caught under the hook which 10 is a very desirable feature. It will be seen, as above stated, that my carrier, because of the fact that it has one hook and is provided with the screw whereby it may be readily detached, is applicable equally well 15 to either "three-ring" or "five-ring" breeching harness, while carriers having two hooks cannot be used for either harness at will.

The reason for making the carrier body 10 in the form of a segment of an annulus 20 or ring is that thus all angles are eliminated and a smooth curved surface is provided at all points of the body except the ears 11 for the engaging ends of harness straps. Thus the same carrier may be used either as shown 25 in Fig. 1 or Fig. 4 without change, and the straps will engage both the side and intermediate portions of the body. At the same time this form of body permits the ready removal of the straps or the replacement

thereof and the shifting of the strap to the 30 proper position, and furthermore permits a slight movement of the several straps upon the carrier, due to the movement of the animal upon which the harness is used.

I claim:—

A trace carrier comprising a body having the form of a segment of an annulus, the ends of said body extending outwardly in spaced parallel relation to each other, a bolt 40 extending through said ends, a spacing sleeve on the bolt, and a hook formed integral with the bright portion of the body diametrically opposite the opening in the body and extending toward said opening, the hook being disposed in a plane at right 45 angles to the plane of the body, said hook extending from the bright portion of the body in spaced approximately parallel relation thereto, the free end of the hook being bent downward and inward into alignment 50 with the body of the carrier.

In testimony whereof I hereunto affix my signature in the presence of two witnesses.

TALY C. THARALSON.
